UNITED STATES PATENT OFFICE.

FRANCIS REYNOLDS AND WILLIAM JOSEPH UNDERWOOD, OF FALL RIVER,
MASSACHUSETTS.

MULE.

SPECIFICATION forming part of Letters Patent No. 698,321, dated April 22, 1902.

Application filed August 31, 1901. Serial No. 73,903. (No model.)

To all whom it may concern:

Be it known that we, FRANCIS REYNOLDS and WILLIAM JOSEPH UNDERWOOD, citizens of the United States, and residents of Fall 5 River, in the county of Bristol and State of Massachusetts, have invented new and useful Improvements in Mules, of which the following is a full, clear, and exact description.

Our invention relates to mules used in textile machinery, and more particularly to a buffer for cushioning the upward stroke or thrust of the part known as the "jumper." In order to fully describe the structure and operation of our invention, it is perhaps advisable to refer briefly to the well-known structure of a mule of the kind commonly used.

In the accompanying drawings like figures indicate like parts in all the views. 20 Figure 1 is an elevation of a mule, showing certain parts broken away and certain details in section. Fig. 2 is a section upon the line 2 2 of Fig. 4 looking in the direction of the arrows. Fig. 3 is a detail section upon the line 3 3 of Fig. 2 looking in the direction of the arrow. Fig. 4 is an end elevation showing the parts as seen by an observer standing to the right of Fig. 2, and Figs. 5 and 6 are details of the shifting rod and various appurtenances.

Upon the bed-frame 1, which is of the usual pattern, is mounted the framework 2 2 3 3, which carries the bulk of the machinery. Upon the overhead shaft 4 are mounted pulleys 5 6, provided with suitable belts, as 7, which cause rotation of the pulleys 8, 9, 10, and 20. From these pulleys 5 and 6 are driven pulleys 8, 9, 10, and 20, 9 being an idle or loose pulley. The clutch members 11 are caused to grip and release by the clutch-collar 12, which is actuated by a series of levers 12', these being in turn actuated by the rod 39', to which the sickle 38' is attached in the usual manner. By means of gear-wheels 13 45 14 15 and a rotary shaft 16 motion is communicated to the bevel-gear 17', thereby causing rotation of the scroll-drum 17, upon which runs the rope 18 for the purpose of moving the carriage outward in the usual manner.

50 To move the carriage inward, the scroll-drum

19 is provided with a rope 19', secured directly to the carriage. By means of the clutch 20' power is applied to the scroll-drum. The shifting arm is shown at 21, the shifting rod at 22, the shifting spring at 23, the shifting dog at 24, and the shifting lever at 25, the same being pivoted upon the shaft 27 and provided with a hook 26. A fixed boss 28 is secured in the end of the cam-like track 28' for the purpose of disengaging the boot-leg 60 by tripping the hook 30 secured thereto, which tripping is accomplished by the movement of the carriage toward the left. The rollers 31 are mounted free to reciprocate vertically, the lower of these rollers directly engaging 65 the surface of the cam-like track 28'.

In Fig. 1 the carriage is represented as partly broken away, the wheel 32, frame 33, and other parts being of the usual pattern. Mounted upon the carriage is a bell-crank 34, 70 provided with two members, one being the swan-neck 34' and the other being the upwardly-projecting arm 32'. The link 35 connects this upwardly-projecting arm with the boot-leg 29. The faller is shown at 36, the 75 horseshoe at 37. These parts are pivotally mounted upon the faller-shaft 37', which is in turn mounted upon the bracket 38, the same being secured to the carriage and movable therewith. The sickle is shown at 38', 80 being connected with the rod 39' for the purpose of actuating the clutch 11, as above described. The vertically-reciprocating member 39, which we style a "jumper," does not move with the carriage, but is mounted upon 85 the frame. The quadrant 40 is provided with a quadrant-arm 41, all of these parts being of the usual type. The bevel-gear 17 is mounted upon the rotary shaft 42 for the purpose of raising and lowering the quadrant 40, 90 as shown more particularly in Fig. 4.

The rod 43 is connected with the rod 22 by means of a fastening 22' in such a manner that the tension of the spring 23 is normally in a direction tending to move the rod 43 toward the left when the apparatus is seen as in Fig. 2. When the carriage slides to the left, the faller-shaft 37' strikes the lever 25, raising the hook 26 and releasing the dog 24, which allows the shifting rod 22 to move to 100

the right, thereby relinquishing the tension of the spring 23. This of course releases the clutch 20 and places the carriage in a position to be moved back again to the right-hand side of the frame—that is, to assume the position shown in Fig. 1. When the carriage is in the position shown in Fig. 1, however, the tension of the spring 23 is upon the shifting rod 22, the spring being held in a compressed position by means of the hook 26. The tendency of the spring, therefore, is to move the rod 43 to the left, thereby exerting tension upon the lever 44, which, however, is prevented from moving in the direction indicated by the boss 45, which is held down by the notch 46 in the lower part of the lever 51, as shown more particularly in Fig. 2. This lever 51 is moved, however, and the notch 46 released from the boss 45 by the head 35, mounted upon the carriage, pressing into engagement with the bolt 53, causing the lower part of the lever 51 to swing to the right. The boss 45 being thus disengaged, the shaft 52 rocks to the left, thus raising the shaft 51 and the jumper 39, which is guided by means of a slot 48, through which passes the bolt 49, secured upon the stationary bracket 50, and is thus kept in position. This movement takes place as the carriage starts to move toward the left and is technically designated as "moving in" and causing the swanneck 34' to pull off the roller 59—that is to say, the mere disengagement of the boss 45 from the notch 46 of the lever 51 is not alone sufficient to cause the jumper 47 to rise, because the same is held down by the swanneck 34'. When, however, the carriage starts in, the swanneck 34' by pulling off from the top of the roller 59 leaves the jumper entirely free and under the tension of the spring 23, as above described, the jumper suddenly rises.

All of the above parts are old, together with the crank 57, link 58, and cranks 55 56, connecting the rod 22 with the shaft 57'. By the travel of the carriage inward and outward, therefore, the jumper is alternately depressed by the swanneck and allowed to spring upward upon being released thereby.

The function of the jumper 39 is to release the rod 43, thus allowing said rod to press the lever 21 toward the left, and thereby cause the clutch members 20 20' to grip. This movement can be understood by inspection of Figs. 2 and 5. The normal tendency of this rod 43 under the tension of the spring 23 is to cause said clutch members to grip. When the swanneck 34' leaves the roller 59, the sudden release of the rod 43 causes the clutch members 20 20' to close with a sudden snap, thus throwing undue strain upon the framework and moving parts. The upward curve of the swanneck slightly retards the release of the jumper, and consequently retards the movement of the rod 43, thus in a measure lessening the shock; but additional means for cushioning the shock are very desirable.

Our invention consists in means for cushioning

the effect of the part which we style the "jumper" as it moves abruptly upward, the part itself being old. To this end we provide a large roller 54 upon the shaft 51 and also provide a composite adjustable lever for the purpose of engaging this roller, and thereby cushioning its upstroke. The lever in question consists of three members 62, 66, 67. The member 67 is curved and the end 66 rests upon the reciprocating rod 70, which slides through brackets 72 and 73 and engages a spring 71 by means of the collar 71'. The lever is normally in the position shown in Fig. 2. By means of the bolts 68 69 the lever can be lengthened or shortened, as desired. By lengthening and shortening the lever, more particularly the curved end thereof, the upstroke or thrust of the jumper can be materially modified, as the roller 54 is thus made to strike a different part of the curved end 67, and therefore to strike the same at slightly-different angles. An adjustable disk 61 is provided with a boss 63 and with a thumb-nut 64, which engages the washer 65, and thereby secures the disk 61 in any desired radial position. The object of making the disk 61 radially adjustable is to place the boss 63 in any radial position within reasonable limits for the purpose of acting as a stop for the composite lever above described. In the position shown in Fig. 2 the spring 71, pressing upward against the inner end of the lever, causes the lever to engage the boss 63, and this limits the downward play of the curved section 67 toward the roller 54. It will be seen, therefore, that by adjusting the position of the disk 61 the lever can be set so as to normally rest at any desired angle and the end 67 can be brought into close proximity to the roller 54 or raised some distance therefrom. By means of this adjustment and the adjustment due to the bolts 69, together with the curvature of the end 67, the cushioning effect of the lever upon the roller 54 can be modified in several different ways.

Having thus described our invention, we claim as new and desire to secure by Letters Patent—

1. An apparatus of the kind described, comprising a jumper, a revoluble member connected therewith, and a buffer engaging said revoluble member for the purpose of cushioning the upthrust of said jumper.

2. An apparatus of the kind described, comprising a jumper, a revoluble roller connected therewith, and a spring-tensioned lever mounted in the path of said roller for cushioning the upthrust of said jumper.

3. An apparatus of the kind described, comprising a jumper, a revoluble roller mounted thereon, a lever engaging said roller for the purpose of buffering the upthrust of said jumper, and means for adjusting the position of said lever relative to said jumper.

4. An apparatus of the kind described, comprising a jumper, a revoluble member connected therewith, and a lever for engaging

said revoluble member and thereby buffing the upthrust of said jumper; said lever being made of interchangeable sections.

5. An apparatus of the kind described, comprising a jumper, a revoluble member connected therewith, a lever engaging said revoluble member for cushioning the upthrust of said jumper, said lever being provided with a curved end for the purpose of modifying 10 the effect of said revoluble member upon said lever.

6. An apparatus of the kind described, comprising a jumper, a revoluble member connected therewith, a lever for engaging said 15 revoluble member and provided with a curved end for modifying the impact of said revoluble member upon said lever, and means for adjusting the position of said curved end of said lever relative to the position of said 20 jumper.

7. An apparatus of the kind described, comprising a jumper, a lever for buffing the upthrust of the same, a normally fixed disk provided with a stop for said lever, and means 25 for securing said disk in a predetermined position, at will.

8. An apparatus of the kind described, comprising a jumper, a lever for buffing the up-

thrust of the same, a spring for normally cushioning said lever, and means for adjusting said lever relatively to said jumper.

9. An apparatus of the kind described, comprising a jumper, a revoluble member connected with the same, a lever for cushioning the upthrust of said jumper and provided 35 with a curved end for engaging said revoluble member, and means for adjusting said lever in different radial positions.

10. An apparatus of the kind described, comprising a jumper, means for guiding the 40 same in a predetermined path, a revoluble member connected with said jumper, a lever provided with a curved end, and means for adjusting said lever in predetermined radial positions, for the purpose of causing said 45 curved end to be engaged at different angles by said revoluble member.

In testimony whereof we have signed our names to this specification in the presence of two witnesses.
